ATOMIZER HEAD

Irving T. Holihan and Walter H. Davis,
Waterbury, Conn.

Application February 25, 1942, Serial No. 432,180

14 Claims.

(Cl. 299—88)

This invention relates to atomizer heads adapted to be applied to a container and capable of being held and actuated with one hand.

Devices of this character as heretofore constructed have, in most instances, been formed with a flexible diaphragm for controlling the flow of liquid from the container to the atomizing head. It is found in practice that the quantity of liquid discharged from such devices is not uniform or great enough for many purposes and the quality or character of the discharge is not always satisfactory.

In accordance with the present invention a different and simpler form of valve means is employed and atomization takes place in such a manner as to produce a substantially uniform discharge containing a relatively large proportion of liquid.

The construction of devices embodying our invention may be varied but the preferred form thereof hereinafter described and shown in the drawing embodies a ball valve which normally tends to close the passage leading to the atomizing head from the container to which the device is applied. The head is provided with means for atomizing liquid in part at least prior to the passage thereof to the discharge opening from which the charge is expelled. This construction is found to be simple and economical to produce and assemble and is also found to provide a substantially uniform discharge containing a relatively high proportion of liquid in a finely atomized form.

One of the objects of our invention is to provide a novel type of atomizer head adapted to be applied to a container and embodying a limited number of parts which are simple in construction and capable of being assembled readily.

Another object of our invention is to provide an atomizer head with novel means for effecting the atomization of liquid.

A further object of our invention is to provide an atomizer head with means for effectively atomizing a relatively large and uniform quantity of liquid.

These and other objects and features of our invention will appear from the following description thereof in which reference is made to the figures of the accompanying drawing.

In the drawing:

Fig. 1 is a vertical sectional view through one preferred form of device embodying our invention,

Fig. 2 is a top plan view of the construction illustrated in Fig. 1, and

Fig. 3 is an exploded view of the construction shown in Fig. 1 with the parts thereof arranged in the order of their assembly.

That form of our invention illustrated in the drawing is particularly designed to be applied to bottles containing perfume, toilet water, shav-

ing lotion or other toilet requisites, but it will be understood that atomizing heads embodying our invention may be used with any type of liquid and may be applied to containers of any form and secured thereto by any suitable or preferred means.

As shown, the atomizing head is provided with a retaining member 2 formed with a lower attaching portion 4 threaded to engage complementary threads 6 on the neck 8 of a bottle or other container. The upper wall portion 10 of the retaining member is of larger diameter than the lower attaching portion and is connected thereto by a shoulder 12. A washer 14 formed of cork composition or other sealing material is located within the upper portion of the retaining member and bears against the shoulder 12 to form a tight seal between the top of the container and the retaining member when the head is screwed onto a container. A stiff washer 16 is located above the cork washer 14 and seals the space between washer 14 and the atomizing elements within the head.

The atomizing element preferably include a cup shaped member 18 having a base 20, the lower face of which bears against the stiff washer 16. The side wall 22 of the cup shaped member is provided with an aperture 24 located adjacent a discharge opening 26 formed in the upper wall portion 10 of the retaining member. The aperture 24 in the cup shaped member is accurately aligned with the discharge opening 26 by suitable means such as the inwardly projecting rib 28 on the retaining member and the complementary indentation 30 in the side wall 22 of the cup shaped member.

The base 20 of the cup shaped member is provided with a centrally located valve seat member 32 in the form of a rivet having the head 34 thereof located within the cup. A passage 36 extends axially through the rivet and is formed with the upper portion thereof enlarged at 38 to form a valve receiving recess, shaped to present a valve seat, against which a ball 40 or other suitable form of valve member may bear. The lower end of the rivet or valve seat member extends below the cup shaped member 18 and is formed to receive a rubber connector 42 or other means for securing a glass tube 44 or the like to the valve seat member for conducting liquid to the recess 38 therein from the container.

Within the cup member 18 is located a plate 46 having the central portion thereof formed with a dome 48, the inner surface of which is spaced a short distance from the upper surface of the rounded head 34 of the rivet or valve seat member 32. The plate 46 thus cooperates with the cup shaped member 18 to form an atomizing chamber communicating with the recess 38 in which the ball valve 40 is located.

The lower surface of the marginal portion 50

of the plate 46 rests upon the upper surface of the base 20 of the cup member 18 and is formed with a groove 52 extending from the atomizing chamber beneath the dome 48 to the aperture 24 in the side wall of the cup shaped member. A second groove 54 is formed in the lower surface of the marginal portion 50 of the plate 46 and extends from a point in the atomizing chamber diametrically opposite to groove 52 to an opening 56 which extends through the plate 46. The groove 54 is generally arcuate in form and is usually longer than the groove 52, since it has been found in practice that this form and length of groove adds to the effectiveness of the device.

The opening 56 in the marginal portion of the plate 46 communicates with the air space 58 within a compressible device such as the rubber bulb 60. The marginal portion of the bulb is located adjacent the wall 22 of the cup shaped member 18 and bears against an annular washer 64 on the upper surface of the plate 46. The upper edge of the wall portion 10 of the retaining member 2 is turned inwardly at 66 over a bead 68 formed on the periphery of the rubber bulb and serves to hold the rubber bulb in place, thereby retaining the cup shaped member 18, plate 46 and the washers in place within the retaining member.

In order to admit air to the container and prevent the formation of a vacuum therein when liquid is drawn from the container the cup shaped member 18 is formed with a groove 70 in the lower surface of the base 20 thereof. The outer end of the groove preferably extends upward as shown at 72 in Fig. 3 on the outer surface of the side wall of the cup whereas the inner end of the groove 70 extends to a point near the centrally located valve receiving member so as to communicate with the interior of the bottle or receptacle to which the atomizing head is attached. In this way air may pass to the interior of the receptacle upon removal of liquid from the receptacle. The stiff washer 16 which is located adjacent the base of the cup serves to prevent the softer cork washer 14 from being pressed into the groove 70 or blocking the same when the head is screwed firmly in place on a container.

The wall portion 10 of the retaining member is formed with a projection 74 adjacent the outlet opening 26 therein so that a space is formed between the retaining member and the cup shaped member. The outer end 72 of the vent groove communicates with this space so that air may pass readily into the receptacle through the vent passage. The space thus formed also serves as a trap to receive and retain any large droplets of liquid that may be expelled through the aperture 24 in the cup shaped member and appears to aid in producing a uniform and satisfactory discharge from the device.

The operation of the construction described is as follows:

When the rubber bulb 60 is first compressed air is forced from the air space therein through the opening 56 in the plate 46 and through the arcuate groove 54 to the atomizing chamber beneath the dome 48 and about the head 34 of the rivet 32 and thence through the groove 52 and the aperture 24 in the cup shaped member so as to be expelled through the discharge opening 26 in the wall portion 10 of the retaining member. Upon release of the rubber bulb it expands due to its inherent resiliency, drawing air inward to the bulb through the same path. The inward flow of air to the bulb produces a partial vacuum in the atomizing chamber causing the ball valve 40 to

be raised from its seat and liquid is thus drawn from the container through the glass tube 44 and the central passage 36 in the rivet into the recess 38 therein. The rounded head 38 of the rivet is spaced only a very short distance from the inner surface of the dome 48 and it is believed that the liquid is largely retained in the upper portion of the atomizing chamber by the capillary action of these surfaces. However, a portion of the liquid may be drawn into the arcuate groove 54 leading to the opening 56 and the air space in the bulb. Thereafter when the bulb is compressed a second time air is forced from the air space within the bulb through the arcuate groove 54 to the atomizing chamber. The arcuate form of the groove 54 is believed to add to the turbulence of the air in entering the atomizing chamber and also agitates and mixes the air with any liquid that has been drawn into the groove 54.

In passing through the atomizing chamber it is thought that most of the air passes about the marginal portion of the head 38 of the rivet and adjacent the edge of the dome 48 in the plate 46 where the cross sectional area is greatest due to the slightly rounded lower edge of the dome. The streams of air flow in opposite directions from the groove 54 and at high velocity past the edges of the film of liquid retained between the upper surface of the head 38 of the rivet and the lower inner surface of the dome. In flowing past the edges of this film of liquid the air picks up the liquid and causing it to be atomized and dispersed in the air and carried with it through the groove 52 from the atomizing chamber to the aperture 24.

As shown in Fig. 2 the aperture 24 is smaller in cross section than the groove 52 so that a back pressure and further turbulence is produced as the air and liquid carried from the atomizing chamber, through the groove 52 are further broken up in this manner so that the charge expelled from the aperture and through the discharge opening in the retaining member is effectively atomized.

In order to center the aperture 24 accurately with respect to the groove 52 and thus insure consistent and effective atomization of the liquid, the cup shaped member 18 is provided with two inwardly extending indexing ribs or indentations for positioning the plate 46. One of these indentations is shown to be the indentation 30 which cooperates with the rib 28 on the retaining member for positioning the cup shaped member with respect thereto, whereas the second indentation is shown at 75. The plate 46 is formed with a notch 76 in the edge thereof for registry with indentation 30 and a second notch 78 which receives the indentation 75. The use of two indexing or positioning notches is found to be most effective in registering the outer extremity of the groove 52 in centered relation with the aperture 24 in the side wall of the cup shaped member. The slight unavoidable play or inaccuracy in the shape and position of the notches 76 and 78 in the plate and in the location of the indentations 30 and 75 resulting from machine operations are thus offset so that only the minimum displacement of the end of the groove with respect to the aperture results.

The ball valve 40 within the valve seat member operates in the manner of the usual ball valve to normally seal the upper end of the passage 36 through which liquid flows into the atomizing chamber. The valve is only raised from its seat when the rubber bulb expands and normally

closes the passage so that evaporation of the liquid in the container will not occur.

While we have shown and described a preferred form of our invention in order to indicate the nature thereof and have described the operation as it is believed to take place, it will be understood that the form, construction and arrangement of the elements employed may be varied considerably without departing from the spirit and scope of our invention and we do not wish to be restricted to any particular theory of operation. Therefore, it should be understood that the embodiment of our invention herein shown and described is not intended to limit the scope of the following claims.

We claim:

1. In an atomizer head adapted to be applied to a container, a cup shaped member, means for conducting liquid to said member, a plate having a surface thereof spaced from said member and cooperating therewith to maintain a film of liquid within said cup shaped member and between said member and plate, means forming channels communicating with the space between said plate and member at diametrically opposite points, said cup shaped member having an aperture in the side wall thereof with which one of said channels communicates, and a compressible bulb having an air space therein communicating with the other channel for forcing air through said space and for expelling air and liquid through the other channel and from said aperture.

2. In an atomizer head adapted to be applied to a container, a cup shaped member having a recess therein, means for conducting liquid from said container to the recess in said cup shaped member, a valve member located in said recess, a plate having a surface thereof which surrounds said valve member and is spaced a relatively short distance from that portion of the inner surface of the cup shaped member which surrounds said recess to retain liquid in the form of a film between said plate and member, a compressible bulb having an air space therein, means forming an air channel extending from said air space to the interior of said cup shaped member for admitting air to the space between said plate and member on compression of said bulb and for drawing liquid into said recess and past said valve member on expansion of said bulb, and means forming an outlet channel communicating with the space between the plate and cup shaped member at a point spaced from the air channel for conducting air and liquid from said space, said cup shaped member having an aperture therein through which air and liquid from the outlet channel may be expelled.

3. In an atomizer head adapted to be applied to a container, a cup shaped member, means for conducting liquid to said member, valve means controlling the flow of liquid through said conducting means, a plate having a surface thereof which surrounds said valve means and is spaced from said member and cooperates therewith to maintain a film of liquid within said cup shaped member and between said member and plate, means forming channels communicating with the space between said plate and member at diametrically opposite points, said cup shaped member having an aperture in the side wall thereof with which one of said channels communicates, and a compressible bulb having an air space therein communicating with the other channel for forcing air through said space and for expelling air and liquid from said aperture on com-

pression of said bulb and for drawing liquid into said space and past said valve means on expansion of said bulb, the channel which communicates with said bulb being arcuate in shape and substantially longer than the oppositely located channel to agitate the air passing to the space between said plate and member.

4. In an atomizer head adapted to be applied to a container, a cup shaped member, means for conducting liquid to said member, a plate having a surface thereof spaced from said member and cooperating therewith to maintain a film of liquid within said cup shaped member and between said member and plate, means forming channels communicating with the space between said plate and members at diametrically opposite points, said cup shaped member having an aperture in the side wall thereof with which one of said channels communicates, and a compressible bulb having an air space therein communicating with the other channel for forcing air through said space and for expelling air and liquid from said aperture, the channel which communicates with said bulb being longer than the other channel and curved in shape to agitate air passing to the space between the plate and member.

5. An atomizing head adapted to be applied to a container and having a cup shaped member with side walls provided with an aperture therein, the bottom of said cup shaped member presenting a rounded upper surface, a plate located within said cup shaped member and presenting a similarly rounded lower surface spaced a relatively short distance from that of the cup shaped member, means for conducting liquid from the container to which the head is applied to the space between said rounded surfaces, a compressible bulb, means forming a channel extending from said bulb to the space between said rounded surfaces to supply air thereto, and means forming a channel extending from the space between said surfaces to the aperture in the side wall of the cup for conducting air and liquid from said space to said aperture.

6. An atomizing head adapted to be applied to a container and having a cup shaped member with side walls provided with an aperture therein, the bottom of said cup shaped member presenting a rounded upper surface, a plate located within said cup shaped member and presenting a similarly rounded lower surface spaced a relatively short distance from that of the cup shaped member, means for conducting liquid from the container to which the head is applied to the space between said rounded surfaces, a compressible bulb, means forming a channel extending from said bulb to the space between said rounded surfaces to supply air thereto, and means forming a channel extending from the space between said surfaces to the aperture in the side wall of the cup for conducting air and liquid from said space to said aperture, said channels communicating with the space between said rounded surfaces at diametrically opposite points.

7. An atomizer head adapted to be applied to a container and having a cup shaped member having the side wall thereof provided with an aperture, the bottom of said cup shaped member presenting a rounded upper surface, a plate located within said cup shaped member and presenting a similarly rounded lower surface spaced a relatively short distance from that of the cup shaped member, the marginal portion of said plate engaging the cup shaped member to define an atomizing chamber, means for conducting liquid

from the container to which the head is applied to said chamber and to the space between said rounded surfaces to form a film of liquid therebetween, a compressible bulb, means forming a channel extending from said bulb to said chamber at a point adjacent one edge of the space between said rounded surfaces to supply air thereto, and means forming a channel extending from a point in said chamber adjacent the opposite edge of the space between said surfaces to the aperture in the side wall of the cup for conducting air and liquid from said chamber to said aperture.

8. An atomizer head adapted to be applied to a container and having a cup shaped member having the side wall thereof provided with an aperture, means located adjacent the bottom of said cup shaped member and presenting an upwardly facing rounded surface with a recess in the center thereof, a plate located within said cup shaped member and presenting a downwardly facing rounded surface spaced a relatively short distance from the upper surface of said means and extending over said recess, means for conducting liquid from the container to which the head is applied to said recess, a valve member located in said recess for controlling the flow of liquid thereto, a compressible bulb, means forming a channel extending from said bulb to the space between said rounded surfaces to supply air thereto, and means forming a channel extending from the space between said surfaces to the aperture in the side wall of the cup for conducting air and liquid from said space to said aperture.

9. An atomizing head adapted to be applied to a container, comprising members presenting spaced surfaces which are sufficiently close to each other to retain a film of liquid therebetween and cooperating to form an atomizing chamber, means for conducting liquid to said chamber, compressible means having an air space therein, means forming an air channel that is curved throughout the major portion of its length to increase the turbulence of air passing therethrough and leading from said air space to said atomizing chamber and communicating with said chamber at one side thereof, means forming an outlet channel communicating with said chamber at the opposite side thereof for conducting air and liquid from said chamber, and means having an aperture therein through which air and liquid from the outlet channel are projected when said compressible means is depressed, the cross-sectional area of said aperture being less than that of the outlet channel whereby atomization of the liquid takes place on passage thereof through said aperture.

10. In an atomizing head adapted to be applied to a container, means forming an atomizing chamber, means formed with an upwardly facing recess therein surrounded by said atomizing chamber, means for conducting liquid to said recess, a compressible device having an air space therein communicating with said chamber at one side of said recess, and means forming a channel communicating with said chamber at the opposite side of said recess for conducting air and liquid from said chamber whereby air is caused to flow through said chamber in a direction to entrain liquid in said recess and promote atomization thereof.

11. In an atomizing head adapted to be applied to a container, means forming an atomizing chamber, means formed with an upwardly fac-

ing dome-shaped surface having a centrally located recess therein surrounded by said atomizing chamber, means for conducting liquid to said recess, a compressible device having an air space therein communicating with said chamber at one side of said recess, and means forming a channel communicating with said chamber at the opposite side of said recess for conducting air and liquid from said chamber whereby air is caused to flow through said chamber in a direction to entrain liquid in said recess and promote atomization thereof; and a ball valve located in said recess and responsive to the pressure of air in said chamber for controlling the passage of liquid to said recess.

15. 12. In an atomizing head adapted to be applied to a container comprising members cooperating to form an atomizing chamber with parallel surfaces spaced apart to retain a film of liquid therebetween and surrounding an upwardly facing recess, means for conducting liquid to said recess from the container, means for varying the pressure of air in said chamber, gravity actuated valve means located in said recess and responsive to the pressure of air in said chamber for preventing the flow of liquid from said recess to the container while permitting the flow of liquid to the recess when the pressure of air in the chamber is reduced, means forming a channel communicating with said chamber through which air and liquid may be expelled from said chamber, one of said members having an atomizing aperture therein with which said channel communicates, and cooperating means on said members for maintaining said channel and aperture in registry.

30. 13. In an atomizing head adapted to be applied to a container, members forming a chamber presenting closely spaced substantially parallel surfaces adapted to retain a film of liquid therebetween, means for conducting liquid to said chamber to form a film therein, valve means located adjacent said parallel surfaces and surrounded by said chamber for controlling the flow of liquid to said chamber, a compressible element having an air space therein communicating with said chamber for forcing air over said surfaces adjacent said film of liquid to entrain said liquid, and means extending about said members and provided with an aperture through which air and entrained liquid may be expelled from said chamber, said compressible element being expandable to draw liquid from said container past said valve means and into said chamber.

35. 14. In an atomizing head adapted to be applied to a container, a cup shaped member, a plate like member located within the cup shaped member and cooperating therewith to form an atomizing chamber having a dome-shaped portion with an upwardly facing recess which is centrally located with respect to the atomizing chamber, means for conducting liquid to said recess, a valve member located in said recess for controlling the flow of liquid thereto, air supply means communicating with said chamber adjacent one side thereof, and means forming an outlet channel communicating with said chamber at a point therein opposite to that with which said air supply means communicate, whereby air passing through said chamber from said air supply means to said outlet channel flows about or across said recess to entrain liquid contained therein and promote atomization thereof.
